FIG. 3

Patented May 17, 1927.

1,628,654

UNITED STATES PATENT OFFICE.

WILLIAM M. CISSELL, OF LOUISVILLE, KENTUCKY.

INLET VALVE FOR BOILERS.

Application filed March 4, 1926. Serial No. 92,219.

This invention relates to an improved inlet valve for boilers or water heaters, and this application constitutes a companion case to applicant's pending application, 5 Serial No. 751,878, filed November 24, 1924.

One of the important objects of this invention is to provide, in a boiler feed regulating device, an automatically operating valve for regulating the level of water in 10 the boiler, the valve itself being positioned in the cold water inlet pipe and therefore not subject to excessive temperature changes.

Another important object of this invention is the provision, in a boiler feed regulating device, of an improved inlet valve of a simplified construction, and which is readily removable so as to facilitate any repairs which might become necessary.

Still another and further important object of this invention is to provide, in an inlet valve for steam boilers or the like, a means for permitting an inward flow of cold water through the valve, which means effectively prevents the backward passage 25 of boiler scale or other foreign elements to the valve seat, thereby affording a positive operation at all times.

Other and further important objects of the invention will be apparent from the disclosures in the accompanying drawings and following specification.

The invention, in a preferred form, is illustrated in the drawings and hereinafter more fully described.

35 In the drawings:

Figure 1 is a vertical elevation showing the improved water regulator of this invention, parts being in section.

Figure 2 is a vertical sectional view of the 40 valve mechanism proper.

Figure 3 is a perspective view showing the one-piece valve seat and valve rod.

As shown in the drawings:

The reference numeral 10 indicates generally a float chamber which can be attached to any steam boiler or water heater, and which is preferably of spherical form, as shown, and has positioned therein a hollow float 12 composed of suitable material. A float supporting stem 14 is affixed to the float 12 in any suitable manner and is pivotally mounted at 16 upon an upright arm 18, the upper end of which overhangs slightly as best shown in Figure 1 to afford 55 a greater leverage.

The extreme end 20 of the float rod is

adapted to co-operate with the upper end of a valve rod 22, which, with its integral valve head 24, is slidably mounted in a housing 26.

As best shown in Figure 2, this housing 26 is screw threaded into a supporting plate 28 which forms a part of the spherical float housing 10.

The upper end of the valve housing 26 which projects into the float chamber is fitted with a plurality of openings 30, these openings, as shown in Figure 2, being formed at an angle of approximately 45° to the walls of the housing 26 and extending 70 upwardly from the outside of the walls. This prevents the passage of boiler scale, sand, or other foreign materials to the interior of the valve housing 26 and thereby maintains the valve seat clean at all times. 75

Extensions 32 are formed integral with the valve head 24 to permit of the free inward passage of water, and a valve head insert 34 is positioned in the valve head 24, this insert being composed of rubber, fibre, 80 or some other suitable material.

A check valve casing 42 in the shape of a T and having a one-way check valve 44 therein is positioned in the interior of the casting 10 and at the bottom thereof with a resistance tube 46 attached thereto; this resistance tube extending upwardly to a point more than half way around the casting 10, thereby making the opening of this resistance tube above the normal water line. 90

On low pressure boilers the raising and lowering of the water due to boiling point pressure has a tendency to raise and lower the float ball 10, which in turn causes pressure on the valve head insert 34, which pressure sometimes results in considerable damage in a short time, more than would ordinarily happen to such a washer where the float balls are stationary, over a period of long usage. The check valve 44 is accordingly placed at one side of the inlet to prevent the water from flowing back into the water feed and the resistance tube 46 will take up the slight upward and downward movement of the water, thereby retaining the 100 float ball in practically stationary position.

A conical valve seat 36 having an opening therethrough for the passage of water is formed integral with the upper end of a fitting 38 which is attached by means of a union 40 to the lower end of the valve housing 26. Removal of the union 40 permits of 110

the complete and ready withdrawal of the entire valve apparatus for purposes of inspection, repairs, cleaning, or the like, and as the entire valve mechanism is positioned in the cold water inlet it will be evident that the damage which ordinarily results from excessive temperature changes when such valve members are positioned in the float chamber, will be effectively prevented.

10 I am aware that many changes may be made and numerous details of construction varied throughout a wide range without departing from the principles of this invention, and I therefore do not purpose limiting the 15 patent granted hereon otherwise than as necessitated by the prior art.

I claim as my invention:

1. A float valve for water feeders, comprising a spherical float chamber, a spherical 20 float in the chamber, a pivoted lever upon one

end of which the float is mounted, an overhanging pivotal support for the lever, a valve rod co-operating with the short end of the float lever, a housing for the valve rod, said housing forming a portion of the cold water supply inlet, and a combined equalizing and overflow tube in the chamber.

2. A float operated valve for water feeders, including in combination, a valve seat and valve member and a housing in which said valve seat and valve member are removably positioned, together with water level stabilizing means in the housing, said stabilizing means including a one way outlet valve and an overflow pipe, the one way valve being 35 positioned below the water line, and the upper end of the overflow pipe being positioned above the normal water line.

In testimony whereof I affix my signature.

WILLIAM M. CISELL.
